CLAIM**DESCRIPTION**

FIG. 1 is an isometric view of a universal port adapter for blood pressure measuring apparatus or the like according to a first embodiment of the design.

FIG. 2 is a plan view showing the bottom of the first embodiment of the design.

FIG. 3 is a cross-sectional view of the first embodiment of the design taken along line 3—3 of FIG. 2.

FIG. 4 is an isometric view of a universal port adapter for blood pressure measuring apparatus or the like according to a second embodiment of the design.

FIG. 5 is a plan view showing the bottom of the second embodiment of the design; and,

FIG. 6 is a cross-sectional view of the second embodiment of the design taken along line 6—6 of FIG. 5.

The broken lines in FIGS. 1, 2, 4, and 5 are included for the purpose of illustrating a portion of the universal port adaptor for blood pressure measuring apparatus or the like that forms no part of the claimed design.
